ILLUMINATED ADVERTISING DEVICE

Max Jacoby, Berlin, Germany

Application April 22, 1938, Serial No. 203,689
In Germany April 24, 1937

16 Claims. (Cl. 40—130)

My invention relates to illuminated advertising devices and it is an object of my invention to provide an improved device of the kind referred to.

To this end, while in the known devices the contour of the device is defined by the signs at the front of the device, that is, the advertising pictures and/or writings, and the frame of the signs, I arrange an illuminated background for defining the contour of the device. This background, or reflector, is arranged in spaced relation at the rear of the free standing, that is to say, base supported only and at least partly translucent or transparent sign and projects beyond one side, or both sides, or beyond the top or the bottom of the sign. Between the sign and the reflector I arrange a source of light which may be an incandescent lamp, and may be rotary if desired, and at the front of the device I provide means such as a strip of sheet metal, for concealing the source of light and preventing dazzling of the spectators.

The effect obtained by the milder reflected light behind the sign is superior to that of direct illumination.

In the accompanying drawings, various embodiments of my invention are illustrated by way of example.

In the drawings:

Fig. 1 is an elevation of one form of the invention,

Fig. 2 is a section on the line 2—2 of Fig. 1, and

Fig. 3 is a plan view, showing a device with a pyramidal reflector resembling the letter U in horizontal section, and forwardly inclined at the top.

Fig. 4 is an elevation of still another form of the invention.

Fig. 5 is a section on the line 5—5 of Fig. 4, and

Fig. 6 is a plan view, showing a device with an arched reflector.

Fig. 7 shows the reflector of the device illustrated in Figs 4 to 6, flattened out.

Fig. 7a is a section on the line 7a—7a of Fig. 7.

Fig. 8 is an elevation, and

Fig. 9 is a plan view of a fan-shaped reflector,

Fig. 10 is an elevation, and

Fig. 11 is a section on the line 11—11 of Fig. 10, showing a device in which signs are supported by a screen of translucent fabric.

It is understood that the expression "translucent" as employed in the following specification and the claims, includes transparent bodies.

Referring now to the drawings, and first to Figs. 1 to 3, the frame of this device has a vertical front plate 1. Punched in this front plate are the words 55 of the desired advertising matter, and colored

translucent material is pasted to the rear face of the plate behind the inscription. Letters 2 are arranged on the front plate 1 and, in the example illustrated, form the word "ATA," this being representative of a matter which is to be advertised. 5

The letters are free standing, that is to say, they are supported solely at the bottom on the front plate 1 and are translucent, and preferably the letters themselves are more diaphanous than the shaded areas by which they are partly surrounded. 10 Arranged behind, and spaced from, the letters 2 is a background 3 which in this example is a flat vertical plate. An incandescent lamp 4 is placed between the back-ground or reflector 3 and the front plate 1, the front plate being made so high 15 that the lamp 4 is concealed and the spectator's eyes are not dazzled.

The reflector is pyramidal, being equipped with a pair of lateral walls 3' which together with the upwardly inclined back of the reflector, make up 20 a pyramidal member whose cross-section resembles the letter U. A pair of horizontal tongues 11 project from the rear face of the front plate 1 and the lateral walls 3' are slotted at 10 for the reception of the tongues. By these means, the 25 pyramidal reflector 3, 3' is secured to the front plate 1.

Such a pyramidal reflector which is open at the front, and whose back is inclined in forward and upward direction, is highly efficient and produces 30 a good illuminating effect.

Referring now to Figs. 7 and 7a an arched reflector 5 for the devices illustrated in Figs. 4 to 6 is made of a flat piece of elastic material which is partly circular and partly rectangular and 35 whose rectangular or base portion has a triangular slot 6. By pulling together the sides of the slot until they abut, and securing them in this position by threading a strip 7 of sheet metal which is riveted to the piece 5 at one side of the 40 slot, through holes 8 at the other side, the upper circular portion of the reflector is arched, as shown in Fig. 5, and the arched portion is substantially shaped like a hollow cone. To facilitate the arching of the piece 5 into a reflector, and its 45 flattening out when not in use, a croze or depressed groove 14 is impressed in the piece 5 from the front side of the piece, as best seen in Fig. 7a. The borders of the croze abut when the piece 5 is arched, and the croze acts like a hinge when the 50 reflector is flattened out by bending it to the rear.

The reflector, after having been arched by causing the edges of its slot 6 to abut, as described, and securing them by the strip 7, is attached to the rear face of the solid lower portion of the front 55

plate by inserting a tongue 12 on the reflector in a pocket 13 on the lower portion.

The letters 2 here form the word "IMI," which is representative of some other matter to be advertised, and the lower portion of the front plate bears the translucent inscription "Cleans everything!"

By arching the reflector, as described, a particularly good effect is produced. The rim of 10 the arched reflector projects forward at the sides and at the top above the letters 2 and thus defines the contour of the device, as described, or of any other shape.

Notwithstanding its arched form, the reflector 15 is easily folded flat. Obviously, the configuration of the slot 6 depends on the shape of the reflector when arched, the edges bordering the slot being generatrix lines of the shape the reflector is arched into, for instance, straight lines in the 20 case of a cone.

In my novel device, the configuration of the outline of the reflector is no longer limited by consideration of the invariable rectangular shape of the known advertising devices. Thus the outline 25 of the arched reflector may be a circle, or other regular curve, or a polygon, or it may be a jagged or wavy line, or the like.

By way of example, Fig. 4 shows a reflector 5 which at the right is defined by a regular curve, 30 for instance, a circle, while at the left it is shaped like a star. It might be corrugated instead, or jagged to any other shape.

The stereoscopic of the display is enhanced by printing or, preferably, impressing in, the reflector 5 straight or curved lines. To a passing spectator, the lines on the reflector accentuate the apparent displacement of the foreground with respect to the background.

Radial lines 9 are printed on, or impressed 40 in, the reflector 5 illustrated in Figs. 4 to 7a, on the circular portion of the plate. Instead of being radial, the imprinted or impressed lines might also be substantially vertical, or they might be curved.

If desired, representations of any desired kind 45 may be placed on the reflector 3 or 5 in the usual manner, or punched from it entirely or partly to obtain particular effects.

By making the reflector like a fan, as shown 50 in Figs. 8 and 9, a good effect is produced and the reflector can be folded and occupies a minimum space when shipped.

For producing the impression that the signs are freely suspended in space, it is desirable that 55 they should be without the bracing flanges illustrated for the letters 2 in Figs. 1 and 4. Such signs, which may be letters and/or pictures, are made of thin paper to make them translucent and this involves the difficulty that on the one hand they require a support and that, on the other hand, flanges are not desirable. This difficulty is overcome by pasting such signs to a screen of translucent fabric, such as chiffon. Glass panes have already been used for this purpose 65 but a fabric is preferable as there is no interference by reflected light.

An example is illustrated in Figs. 10 and 11. A frame 15 is arranged in front of a reflector 5 and a screen 16, of chiffon or other translucent 70 fabric, is inserted in the frame. Pasted to the front side of this fabric 16, and only connected to the frame 15 at its feet, is a female figure 17 drawn on translucent material, and above the figure is arranged the inscription "Puder" printed 75 on similar material and also pasted to the screen

16. It is obvious that the figure 17 would be practically unsupported without the fabric to which it is pasted.

In order to obtain better adhesion of the figure 17 to the screen, its mirror counterpart 18 5 is made of thin and translucent material, and pasted to the back of the fabric 16 in registering relation to the figure 17 at the front. The paste from the back of the figure 17 oozes through the meshes of the fabric and connects the two figures which are thus securely anchored to each other, and to the fabric. Besides, the color effect is enhanced, in case of translucent arrangement, by the mirror counterpart 18 at the back. Obviously, the same method may be applied to 15 letters, numerals, etc.

While I have herein shown and described certain preferred embodiments of my invention, I wish it to be understood that I do not confine myself to all the precise details herein set forth 20 by way of illustration, as modification and variation may be made without departing from the spirit of the invention or exceeding the scope of the appended claims.

I claim:

1. In an illuminated advertising device, a free standing at least partly translucent sign, a free standing reflector in the form of a hollow body arranged in spaced relation at the rear of the sign and projecting beyond at least one side 30 of the sign, said reflector being adapted to be folded flat, a source of light arranged between the sign and the reflector, and means at the front of the device for concealing the source of light.

2. In an illuminated advertising device, a free standing, at least partly translucent sign, a free standing concave reflector in the form of a hollow body arranged in spaced relation at the rear of the sign and projecting beyond at least one side of the sign, said reflector being adapted to be folded flat, a source of light arranged between the sign and the reflector, and means at the front of the device for concealing the source of light.

3. In an illuminated advertising device a free standing at least partly translucent sign, a free standing arched reflector in the form of a hollow body arranged in spaced relation at the rear of the sign and projecting beyond at least one side of the sign, said reflector being adapted to be folded flat, a source of light arranged between the sign and the reflector, and means at the front of the device for concealing the source of light.

4. In an illuminated advertising device, a free standing, at least partly translucent sign, a free standing arched reflector in the form of a hollow body arranged to project beyond the top and the sides of the sign, and in spaced relation at the rear of the sign, said reflector being adapted to be folded flat, a source of light arranged between the sign and the reflector, and means at the front of the device for concealing the source of light.

5. In an illuminated advertising device a free standing, at least partly translucent sign, an arched reflector in the shape of a flat piece of elastic material defining a slot bordered by two generatrix lines of the arched configuration of the reflector, the reflector being arranged in 70 spaced relation at the rear of the sign and projecting beyond at least one side of the sign, a source of light arranged between the sign and the reflector, and means at the front of the device for concealing the source of light.

6. In an illuminated advertising device, a free standing, at least partly, translucent sign, an arched reflector in the shape of a flat piece of elastic material defining a slot bordered by two generatrix lines of the arched configuration of the reflector, means for holding the sides of the slot abutted against each other, the reflector being arranged in spaced relation at the rear of the sign and projecting beyond at least one side of the sign, a source of light arranged between the sign and the reflector, and means at the front of the device for concealing the source of light. 5
7. In an illuminated advertising device, a free standing, at least partly translucent sign, an arched reflector in the shape of a flat piece of elastic material defining a slot bordered by two generatrix lines of the arched configuration of the reflector and a croze open at the front side of the reflector, the reflector being arranged in spaced relation at the rear of the sign and projecting beyond at least one side of the sign, a source of light arranged between the sign and the reflector, and means at the front of the device for concealing the source of light. 10
8. In an illuminated advertising device, a free standing, at least partly translucent sign, a reflector bordered by a jagged line and arranged in spaced relation at the rear of the sign and projecting beyond at least one side of the sign, a source of light arranged between the sign and the reflector, and means at the front of the device for concealing the source of light. 15
9. In an illuminated advertising device, a free standing, at least partly translucent sign, a reflector bordered by an undulated line and arranged in spaced relation at the rear of the sign and projecting beyond at least one side of the sign, a source of light arranged between the sign and the reflector, and means at the front of the device for concealing the source of light. 20
10. In an illuminated advertising device, a free standing, at least partly translucent sign, a reflector bordered by a curved line and arranged in spaced relation at the rear of the sign and projecting beyond at least one side of the sign, a source of light arranged between the sign and the reflector, and means at the front of the device for concealing the source of light. 25
11. In an illuminated advertising device, a free standing, at least partly translucent sign, a fan-shaped reflector arranged in spaced relation at the rear of the sign and projecting beyond at least one side of the sign, a source of light arranged between the sign and the reflector, and means at the front of the device for concealing the source of light. 30
12. In an illuminated advertising device, a free standing, at least partly translucent sign, a fan-shaped folding reflector arranged in spaced relation at the rear of the sign and projecting beyond at least one side of the sign, a source of light arranged between the sign and the reflector, and means at the front of the device for concealing the source of light. 35
13. In an illuminated advertising device, a free standing, at least partly translucent sign, a reflector having opaque strips and arranged in spaced relation at the rear of the sign and projecting beyond at least one side of the sign, a source of light arranged between the sign and the reflector, and means at the front of the device for concealing the source of light. 40
14. In an illuminated advertising device, a free standing, at least partly translucent sign, a reflector having strip-shaped impressions and arranged in spaced relation at the rear of the sign and projecting beyond at least one side of the sign, a source of light arranged between the sign and the reflector, and means at the front of the device for concealing the source of light. 45
15. In an illuminated advertising device, a screen of translucent fabric, a translucent sign secured to the screen, a reflector arranged in spaced relation at the rear of the screen and projecting beyond at least one side of the sign, a source of light arranged between the screen and the reflector, and means at the front of the device for concealing the source of light. 50
16. In an illuminated advertising device, a screen of translucent material, a translucent sign, pasted to one side of the fabric forming the screen, a mirror image of the sign, also made of translucent material, pasted to the other side of the fabric and registering with the first-mentioned sign, a reflector arranged in spaced relation at the rear of the screen and projecting beyond at least one side of the sign, a source of light arranged between the screen and the reflector, and means at the front of the device for concealing the source of light. 55

MAX JACOBY. 50
